CLAIM

We claim the ornamental design for a device for applying negative pressure to a wound, as shown and described.

DESCRIPTION

FIG. 1 is a front, top and left side perspective view of a device for applying negative pressure to a wound.

FIG. 2 is a top plan view thereof.

FIG. 3 is a front elevation view thereof.

FIG. 4 is a rear elevation view thereof.

FIG. 5 is a right side view thereof.

FIG. 6 is a left side view thereof; and,

FIG. 7 is a bottom view thereof.

The broken lines in the drawings that are immediately adjacent to the shaded areas represent an unclaimed boundary of the claimed design. The broken lines showing the remainder of the device are for illustrative purposes only and form no part of the claimed design.
